UNITED STATES PATENT OFFICE.

JOHN J. CURRAN, OF CHICAGO, ILLINOIS.

LUMBER-DRIER.

SPECIFICATION forming part of Letters Patent No. 274,282, dated March 20, 1883.

Application filed April 10, 1882. (No model.)

To all whom it may concern:

Be it known that I, JOHN J. CURRAN, of Chicago, in the county of Cook and State of Illinois, have invented certain new and useful improvements in Lumber-Driers; and I do hereby declare that the following is a full, clear, and exact description thereof, reference being had to the accompanying drawings, and to the letters of reference marked thereon, which form a part of this specification.

This invention relates to improvements in lumber-driers having the general features of construction shown in reissued Letters Patent of the United States Nos. 8,840 and 8,846, dated August 12, 1879, said improvements having more especial reference to the three following features, to wit: first, the air-heating chamber, located beneath the drying-chamber; second, the deflecting-board by which the heated air is directed as it enters the drying-chamber; and, third, the construction and location of the chimney or flue by which the air leaves the drying-chamber.

The first of these improvements has for its object to secure a more steady supply of air to the heating-chamber, and to obviate the liability existing under the old construction of chilling the steam heating-pipes; and to this end it consists in providing an intermediate door or register cutting off an anterior chamber in which the cold air is partially arrested and retained, and whence it passes to the heating-chamber proper in a steadier flow and in a partially-warmed condition.

The second branch of my improvements embraces two features, one having for its object to more perfectly direct the air horizontally into and beneath the first car of lumber, instead of allowing it to first rise to the top of the drying-chamber. By this means the lower portions of the lumber are more thoroughly acted upon by the heated air and the entire body of lumber more evenly dried. The other feature of this branch of my invention has for its object to direct the heated air into the middle of the first lumber pile as well as into its lower portions, so that the middle of the boards will be dried equally with their ends. A general advantage of this branch of my improvement is found in the avoidance thereby of a puffy movement of the air-current incident in some measure to the old construction, in which

the rising and horizontal currents produced objectionable eddying and spasmodic or intermittent forward movements of the air through the drying-chamber. To these ends this part of my improvement consists, primarily, in the combination, with the door heretofore used, of a horizontal deflecting board or hood resting against or supported proximate to the adjacent lumber pile, and, secondarily, in lateral wings applied to said hood, by which the air is retained at its sides and prevented from escaping in too large volume about the ends of the pile.

The third branch of my invention embraces two features, having for their objects, first, to strengthen the draft through the central part of the kiln; and, second, to make the draft more uniform and to prevent interruption thereof by sudden movements of the external or wind currents. To these ends my invention relating to the chimney consists, first, in locating the narrow portion of the chimney centrally as to the drying-chamber; and, second, in providing a lateral deflection therein, as will be more fully set forth.

In the drawings, Figure 1 is a central vertical longitudinal section of a lumber-drier containing my several improvements. Fig. 2 is a front elevation. Fig. 3 is a perspective view of the deflecting hood and register, with its lateral wings shown in relation to the tracks; and Fig. 4 is a perspective view of said hood and wings folded in a horizontal position, detached.

A is the drying-chamber of the kiln, having the usual inclined floor A', ceiling parallel to the floor, tracks a, and end doors, A² A³, for the admission and discharge of the lumber piles stacked on cars fitted to the tracks a.

B is the most advanced car-load of lumber in said chamber A, others in practice occupying the remainder of said chamber, and being successively advanced to the position of B prior to being discharged at A³. Said lumber-piles are built up in the usual manner in rectangular form to proximate the side walls and the ceiling of drying-chamber.

C is the air-heating chamber, provided with steam-pipes C', arranged preferably in transverse gates, as shown, said chamber communicating with the drying-chamber A by the passage a' at the rear end of the kiln through

the floor A'. The passage a' is located between the tracks a a, which are situated each about one-fourth the width of the chamber inward from the adjacent side of the latter.

5 D D' D² is the chimney, leading from the front end of the drying-chamber, as shown.

Heretofore these kilns have been constructed with but a single chamber for heating the air, extending and provided with heating-pipes 10 throughout the entire length of the kiln. Cold air admitted immediately and directly to the pipes in a violent current through the register or doors E would sometimes chill said pipes, impairing their circulation, or even freezing 15 their contained water of condensation, thereby in cold and windy weather interrupting or interfering seriously with the operation and use of the kiln. To remedy this defect the anterior chamber, F, is cut off from the front end of 20 the space beneath the kiln by the broad register or door F', and the heating-pipes C' are confined to the rear and longer chamber, C, as shown in Fig. 1. The cold air, being admitted first to the chamber F, is therein commingled 25 with warmer air previously admitted, so as to lose its chilling effect, and is, moreover, retarded and regulated in its passage to the pipes through the register F', so as to flow evenly forward into and through the heating-chamber C.

The deflector heretofore applied to the passage a' has consisted of a plain door hinged to the rear edge of the opening and adapted to be set more or less inclined toward the adjacent lumber-pile B. Such a deflector does not, however, operate to prevent the main portion of the heated air from rising into the space g and thence passing forward near the top and about the sides of the chamber, drying 30 the upper boards and the ends of the boards more completely than the remaining portions. This effect is in some degree remedied by the depending curtain H, but not completely, while the air by first rising into the space g, as stated, before passing forward is materially interrupted in its progress, much to the detriment of the draft of the kiln, both as to its 35 steadiness and force.

G indicates my improved deflector as a 40 whole. It consists of the original door, G', already described, of size suitable to close the passage a' when lowered, said passage being located between the tracks a a, as better shown in Fig. 1. To the free edge of the door G' is hinged the similar flap, G², which may be supported in a horizontal position against the lumber-pile B by means of a stick thrust beneath it between the boards of said lumber-pile or otherwise. By means of the hood G² 45 the door G' is not so much inclined forward as to impede the draft, and the air-current is in the first instance mainly directed into the lower central portion of the first lumber-pile, where its effects are most needed, for the reason that 50 in the positions previously occupied by the car the principal effects of the heated air have

been expended on other portions of the lumber. As a means of still more perfectly directing the air into the central part of the lumber-pile B, side wings, G³, are preferably 55 added to the parts G' and G² by hinges connecting them with the part G². These side wings measurably prevent lateral escape of the air from beneath the deflector, and may serve to support the remaining parts, as seen 60 in Fig. 3. When the door is lowered to allow the car to be rolled out of the kiln, the several parts, G', G², and G³, may be folded, as shown in Fig. 4.

Kilns have been heretofore constructed with 65 a broad chimney extending entirely across the kiln, and others have been made with two narrow chimneys located one at each side of the kiln. The former has been found objectionable by reason of the great extent of surface exposed to the wind. The latter form has been found to be an economical construction in building two or more kilns side by side, because one chimney could be made to serve for two adjacent kilns; but this location of 70 the chimneys has been found to favor the natural and objectionable tendency of the air to pass along the sides of the drying-chamber in spite of other means employed to prevent it. Wherefore I have here shown the chimney 75 made of the full width of the kiln at its lower portion, D, but narrowed in its upper portion, D², which is centrally placed, as indicated in Fig. 2. By this means the air-current is given substantially equal force throughout the entire width of the kiln, the central position of the upper part of the flue practically balancing or neutralizing the tendency to a more forcible draft along the sides of the drying-chamber.

The anterior chamber, F, and the deflector G, above described, contribute materially to evenness or steadiness of draft in the kiln; but as a means more especially directed to this object, the chimney is provided with an offset, D', and a horizontal deflecting-board, d, by which the current is sharply deflected, as indicated by the arrows, Fig. 1. By means of this deflection in the flue the draft of the kiln is much less affected by sudden changes in the 80 direction and velocity of the outer wind. As here shown, such deflection of the flue or chimney passage is located in the lower and broader part of the chimney; but it is believed that substantially the same effect will be obtained 85 if located elsewhere.

The depending curtain J, shown in former 90 patents as forming the extension of the chimney below the ceiling of the drying-chamber, is here shown in connection with the improved 95 device for hoisting the same, which consists of the cord j, fastened by one end at j' and trained beneath the roller J' and over the pulley J², located in the chimney-passage. By 100 locating the pulley J² in the position shown 105 the cord may be made to raise the roller J' with the curtain folded thereon to or above the

level of the ceiling, so as to allow the lumber piles to pass through, reaching very near to the ceiling. This is important, since it is found that piling the lumber to a height just barely clearing the ceiling is the most effective means of preventing undue pressure of the air along the top of the drying-chamber.

I claim as my invention—

1. In a lumber-drier, the combination, with the air-heating chamber C, of the anterior chamber, F, provided with the registers E and F', substantially as described, and for the purposes set forth.

2. In a lumber-drier of the general description shown, the deflector composed of the parts G' and G², hinged to each other, and the former hinged to the floor, arranged with reference to the passage a', substantially as described, and for the purpose specified.

3. In a lumber-drier of the general description shown, the deflector G, composed of the parts G', G², and G³, arranged with reference

to the passage a', substantially as described, and for the purposes set forth.

4. In combination with the horizontal drying-chamber A, admitting hot air at one end and discharging the same at the other, and with the traveling lumber-pile proximating the walls and ceiling of the chamber, the discharge flue or chimney, made of the full width of said chamber at the bottom and terminating in a narrower central flue at the top, substantially as shown.

5. In a lumber-drier, the discharge-flue having an offset, D', and deflector d, substantially as and for the purposes set forth.

In testimony that I claim the foregoing as my invention I affix my signature in presence of two witnesses.

JOHN J. CURRAN.
